UNITED STATES PATENT OFFICE.

WILLIAM G. WEHR, OF EAST CLEVELAND, OHIO, ASSIGNOR TO THE CLEVELAND CRANE & ENGINEERING COMPANY, OF WICKLIFFE, OHIO, A CORPORATION OF OHIO.

GRAB.

Application filed September 18, 1925. Serial No. 57,076.

To all whom it may concern:

Be it known that I, WILLIAM G. WEHR, a citizen of the United States, residing at East Cleveland, in the county of Cuyahoga and State of Ohio, have invented a certain new and useful Improvement in Grabs, of which the following is a full, clear, and exact description.

This invention relates to grabs and more particularly to a grab designed for engaging and lifting rectangular bodies such as bales, boxes or piles of sheet metal, the device herein shown having been designed particularly for handling piles of tin plate.

One of the principal objects of the present invention is to provide a grab which is readily adjustable for engagement with square or rectangular bodies of different shapes and sizes. The further object of the invention is to provide a grab in which the load engaging members move by gravity to load engaging position so that it is held in tight engagement with the load by the weight of the load, and further, to provide the grab with means for supporting the same upon the body to be lifted in such manner that it can be adjusted to a position such that it will properly engage the body to be lifted and may then be released so that it will move by gravity into gripping engagement therewith.

The following description and accompanying drawings set forth in detail certain means embodying the invention, the disclosed means, however, constituting but one of the various mechanical forms in which the principle of the invention may be employed.

Reference should be had to the accompanying drawings forming a part of this specification in which Fig. 1 is a side elevation of the grab in load engaging position; Fig. 2 is a side elevation of the grab viewed in a direction at right angles to the direction in which the grab is viewed in Fig. 1; Fig. 3 is a top plan view of the grab; Fig. 4 is a vertical section on an enlarged scale through the central supporting member of the grab.

Referring to the accompanying drawings, the grab is provided with a centrally disposed load supporting member 1 from which the load gripping members are suspended and to which the hoist cable is attached. Intermediate the ends thereof the supporting

member 1 has formed therein a sheave case 55 2 in which is mounted a sheave 3 which receives the loop of a hoist cable 4, the sheave case 2 being provided with openings 5 at the top thereof for the passage of the cable 4. The supporting member 1 60 is provided with a cylindrical bearing portion 6 which projects upwardly from the top of the sheave case 2, and with a lower cylindrical bearing portion 7 which projects downwardly from the bottom of the 65 sheave case 2 in axial alignment with the cylindrical bearing portion 6. Two collars 8 and 9 are rotatably mounted upon the projection 6 and two similar collars 11 and 12 are rotatably mounted upon the projection 70 7 immediately beneath the sheave case 2. The collars 8 and 9 are retained against the top of sheave case 2 by means of a nut 13 upon the upper end of the projection 6 and the collars 11 and 12 are retained against 75 the under side of the sheave case 2 by means of a collar 14 fixed to the projection 7 below the lowermost collar 12. The collar 8 is provided with outwardly projecting ears 15 at diametrically opposite points thereon, and 80 the collar 9 is provided with similar outwardly projecting ears 16. The collars 11 and 12 are also provided with outwardly projecting ears 15 and 16 which are positioned directly beneath the corresponding 85 ears on the collars 8 and 9. Upper and lower radially disposed links 17 and 18 are pivoted at their inner ends to the outwardly projecting ears 15 and 16 of the collars 8, 9, 11 and 12. The superposed pairs of links 90 17 and 18 are parallel and are pivotally connected at their outer ends to vertically disposed load engaging bars 19. The ears 15 on the collars 8 and 11 are in vertical alignment and each of the two pairs of links connected to the ears 15 are connected to one of the vertical load engaging bars 19. The ears 16 on the collars 9 and 12 are also in vertical alignment and the two pairs of links connected to the ears 16 are connected to

100 the other two load engaging bars 19. Each pair of diagonally opposite load engaging bars are thus connected through their supporting links with the same rotatable collars on the central supporting member and 105 may be turned about the axis of the supporting member. The load supporting bars 19 are in the form of inwardly facing angle

bars and the links 17 and 18 are connected thereto by horizontal pivot pins 20 which connect the ends of the links 19 to brackets 21 secured between the flanges of the angle bars 19. The bars 19 engage with the corners of the rectangular pile, or other rectangular body to be lifted, and are provided at their lower ends with inwardly extending foot portions or ledges 22 upon which the 10 load rests while being lifted. The projection 7 extends downwardly below the retaining collar 14 and is provided with an enlarged foot portion 23 which may be provided with a rubber pad 24 on the under side 15 thereof for engagement with the top of the pile of sheet metal or with the top of any rectangular object to be lifted. The lower portion of the projection 7 carries two collars 25 and 26 which are slideable vertically 20 and are also rotatable thereon. The collars 25 and 26 are provided with radially extending arms 27 and 28 which are connected by links 29 and 30 with the lower bar actuating links 18. The lower collar 26 carries a 25 radially disposed spring pressed latch pin 31 which is adapted to engage with a circumferential groove 32 formed on the projection 7, an operating cable 33 being connected with the latch pin 31 for releasing 30 the same from the projection 7. The links 17 and 18 are inclined downwardly as shown in Figs. 1 and 2 when the bars 19 are in load 35 engaging position, and it will be obvious that the weight of the bars 19 and the connecting links will tend to move the bars to load engaging position. If the bars 19 be pulled outward or be lifted with respect to the load supporting member 1, the links 17 and 18 will be swung upwardly toward horizontal position moving the bars 19 outwardly from the central supporting member. The upward movement of the lower 40 links 18 will cause the collars 25 and 26 to slide upward on the projection 7 and when the latch pin 31 registers with the groove 32 in the projection 7 it will snap into engagement with the groove and lock the load engaging members in extended positions.

In the operation of the device the load engaging bars, preparatory to picking up a load, are shifted to extended positions and are held extended by the latch 31. The grab is then moved to position over the pile or object to be lifted, and is lowered until the foot 23 of the central supporting member rests upon the pile adjacent the center thereof. The diagonally disposed pairs of load engaging bars are then adjusted by turning the same with their supporting links 50 about the axis of the central supporting member until they are positioned in line with the diagonally opposite corners of the pile. The supporting links are then released by releasing the latch pin 31 whereupon the load engaging bars will drop by gravity and

in their downward movement will be swung inwardly into engagement with the corners of the pile by their connecting links 17 and 18. The hoisting cable 4 is then wound up and the grab will be lifted bodily until the supporting ledges 22 at the lower ends of the bars 19 engage with the bottom of the pile. By reason of the parallel arrangement of the load gripping bars 19 the gripping of a pile of sheets by the bars will tend to force the edges of the sheets into alignment and straighten the pile. After the supporting ledges 22 come into engagement with the bottom of the pile, further upward movement of the grab will cause the pile to be lifted off its support. After the load has been conveyed to the desired point, the grab is lowered until the weight of the load is transferred to the ground or to the pile on which the load is deposited; whereupon further downward movement of the central supporting member 1 will cause the inner ends of the links 17 and 18 to be swung downwardly toward horizontal position forcing the bars 19 outwardly out of engagement with the load. At the same time the latch 31 snaps into engagement with the groove 32 on the supporting member locking the grab in extended position so that it may be lifted clear of the released load and is held in proper position to be lowered over another load.

Having described my invention, what I claim is:

1. A grab comprising a central supporting head, a plurality of load gripping devices carried by the head, a pair of superposed links connecting each gripping device to the head, the links of each pair being connected to the head for movement about horizontal axes and about the vertical axis of the head.

2. A grab comprising a central supporting head, a plurality of members mounted on said head to turn independently about the vertical axis thereof, and load gripping devices carried by said members and movable therewith about the axis of the head.

3. A grab comprising a central supporting head, a plurality of superposed collars mounted to turn independently upon said head, certain of said collars being movable vertically on said head, load gripping devices each having a link connection to a plurality of collars including one of the vertically movable collars, and releasable means for holding said last mentioned collars against vertical movement to retain the gripping devices in a given position.

4. A grab comprising a central supporting member, a plurality of gripping members, a pair of links connecting each gripping member to the supporting member, and means connecting the links to the supporting member to permit movement about horizon-

- tal axes to open and close the gripping members and independent movements thereof about a vertical axis to permit relative adjustment of the gripping members.
5. A grab comprising a central supporting member, and two load gripping devices carried thereby, each gripping device comprising a pair of diametrically opposed gripping members and means connecting the same to the supporting member for movement toward and from each other, said gripping devices being positioned in planes which intersect axially of the supporting member and being adjustable angularly one 10 with respect to the other.
6. A grab comprising a central supporting member, two pairs of gripping members carried by said supporting member, the gripping members of each pair being on opposite sides of the supporting member, and means connecting each pair of gripping members to the supporting member for simultaneous movement toward and from the supporting member, said connecting means 20 permitting angular adjustment of one pair of gripping members with respect to the other.
7. A grab comprising a central supporting member, two pairs of gripping members carried by said supporting member, the gripping members of each pair being on opposite sides of the supporting member, and links connected by horizontal pivots to said supporting and gripping members, the links 30 connecting the gripping members of one pair to the supporting member, being angularly adjustable about a vertical axis.
8. A grab comprising a central supporting member, two pairs of gripping members carried by said supporting member, the gripping members of each pair being on opposite sides of the supporting member, and vertically swinging links connecting gripping members to the supporting member, 40 the gripping members and connecting links of one pair being adjustable angularly about the supporting member.
9. A grab comprising a central supporting member, a plurality of collars mounted for independent turning movement on the supporting member, links pivoted at their inner ends to said collars, and gripping members carried by the said links at their outer ends.
- 50
10. A grab comprising a central supporting member, a plurality of collars mounted for independent turning movement on the supporting members, a pair of links connected to each collar at diametrically opposite points, and gripping members carried by the said links at their outer ends.
- 55
11. A grab comprising a central supporting member, four pairs of superposed parallel links pivoted at their inner ends to said supporting member said pairs of links being angularly disposed with respect to each 60 other, and a vertical load engaging member pivotally connected to the outer ends of the links of each pair.
12. A grab comprising a central supporting member, four pairs of superposed parallel links pivoted at their inner ends to said supporting member, a vertical load engaging member pivotally connected to the outer ends of the links of each pair, and means interposed between the links and supporting member for releasably securing the load engaging members in extended positions.
- 70
13. A grab comprising a central supporting member, four pairs of superposed parallel links pivoted at their inner ends to said supporting member and a vertical load engaging member pivotally connected to the outer ends of the links of each pair, certain of said pairs of links with their load engaging members being angularly adjustable toward and from other of said load engaging members.
- 75
14. A grab comprising a central supporting member having vertically disposed cylindrical bearing portions, collars rotatably mounted on said bearing portions, radially disposed vertically swinging links pivotally connected at their inner ends to said collars, said links being arranged in four pairs, each pair being superposed and parallel, each pair of links being diametrically opposite another pair and connected to the same collars as the links directly opposite thereto, four vertical inwardly facing angle bars, each having an inwardly projecting supporting portion at its lower end, and each connected to a pair of superposed parallel links.
- 85
- 90
15. A grab comprising a central supporting member having vertically disposed cylindrical bearing portions, collars rotatably mounted on said bearing portions, radially disposed vertically swinging links pivotally connected at their inner ends to said collars said links being arranged in four pairs, each pair being superposed and parallel, each pair of links being diametrically opposite another pair and connected to the same collars as the links directly opposite thereto, and means for releasably securing the links in positions in which the load engaging members are spread apart.
- 105
- 110
16. A grab comprising a supporting member having a sheave case intermediate the ends thereof and cylindrical portions projecting upwardly and downwardly from the sheave case, a pair of collars rotatably mounted on each cylindrical portion, radially extending vertically swinging links connected at diametrically opposite points to each collar, four load engaging members each connected to a link extending from a collar of the upper pair and to a link extending from a collar of the lower pair, collars rotatable and slidable upon the lower cylindrical portion of the supporting member,
- 115
- 120
- 125
- 130

each of said last mentioned collars being connected to one of said links, and a latch carried by the lowermost of said collars and engageable with the supporting member to releasably hold the said collars in their uppermost positions.

17. A grab comprising a supporting member having a sheave case intermediate the ends thereof and cylindrical portions projecting upwardly and downwardly from the sheave case, a pair of collars rotatably mounted on each cylindrical portion, radially extending vertically swinging links connected at diametrically opposite points to each collar, four load engaging members

each connected to a link extending from a collar of the upper pair and to a link extending from a collar of the lower pair, collars rotatable and slidable upon the lower cylindrical portion of the supporting member, 20 each of said last mentioned collars being connected to diametrically opposed links, and means for limiting the vertical movements of said last mentioned collars, said supporting member having a foot portion at 25 its lower end adapted to rest upon a load to be lifted.

In testimony whereof, I hereunto affix my signature.

WILLIAM G. WEHR.
